UNITED STATES PATENT OFFICE.

ERNEST A. DE WOLF, OF MANSFIELD, MASSACHUSETTS, ASSIGNOR, BY MESNE ASSIGNMENTS, TO UNIVERSAL WINDING COMPANY, OF BOSTON, MASSACHUSETTS, A CORPORATION OF MASSACHUSETTS.

ADJUSTABLE SUPPLY-HOLDER.

1,216,782.

Specification of Letters Patent. Patented Feb. 20, 1917.

Application filed October 24, 1914. Serial No. 868,466.

To all whom it may concern:

Be it known that I, ERNEST A. DE WOLF, a citizen of the United States, residing at Mansfield, in the county of Bristol and State 5 of Massachusetts, have invented certain new and useful Improvements in Adjustable Supply-Holders, of which the following is a specification.

My invention relates to improvements in 10 supply-holders for holding cops or bobbins while delivering the material therefrom in various processes of the textile arts. The object of my improvement is to provide an adjustable cop- or bobbin-holder having a 15 spindle which can be set at different angles to adapt the bobbin or cop to be inclined with its axis in line with the point to which the yarn is delivering. My new improvement provides for more accurate setting of 20 the bobbins so as to insure free and unrestricted delivery of the yarn therefrom and is of particular advantage for use on creels or with other apparatus where a large number of ends are being supplied. By adapting 25 the individual bobbin-holders for quick and easy adjustment the several yarns can be directed to the tension-devices at equal angles so that a more uniform tension will be applied to all of the ends and there will be 30 less liability of breaking or straining the material.

The invention is fully described in the following specification, illustrated by the accompanying drawings, in which like reference 35 characters designate like parts. In the drawings:—

Figure 1 is an enlarged, detail view of the essential parts of the device with the right-hand side shown in section to illustrate the 40 structural arrangement of the spindle-adjusting means; and

Fig. 2 is a view showing the method of securing the spindle-supports to the uprights of a creel adapted to hold a plurality 45 of bobbins delivering their ends in multiple.

Referring first to Fig. 1, A designates the main supporting-bracket or standard for the bobbin-spindles which is preferably constructed in the form of a cross-arm having 50 its ends cupped out or recessed to provide sockets a, a. Each bracket A is adapted to support two bobbin-spindles S, S which are of suitable diameter to fit the bores b' in the base of the bobbins or yarn-holders

b, b. The spindles S are formed with 55 spherical enlargements s at their ends adapted to fit the sockets a in the ends of the arm A, and are provided with transverse holes s' for receiving suitable bolts D. Held on the bolts D are cup-like washers or caps 60 C formed with recesses c which are also adapted to the spherical surfaces of the ball-like ends s of the spindles S. The bolts D extend through axial holes c' in the caps C, and reaching through the enlarged bores s' 65 of the balls s are screwed into the ends of the arm A. By tightening the bolts D the caps C can be clamped against the balls s on the spindles S to bind the latter in the sockets a and secure them in fixed relation 70 to the bracket A. It will be observed that the bore s' through the ball s is somewhat greater in diameter than the body of the bolt D so as to allow sufficient play to provide for lateral movement of the spindle 75 S in adjusting it in position. The rims of the sockets a are cut away at a' and the caps C also have cut-out sections c' to accommodate the reduced neck-portions s' of the spindles S during their lateral adjustment. A still wider range of adjustment of 80 each spindle in a direction at right-angles to the arm A is accomplished through the turning movement of the ball s on the bolt D.

Where the bobbin-spindles are set to point 85 downwardly means must be provided for holding the bobbins from slipping off and a simple arrangement for this purpose is shown at the right-hand in Fig. 1. This consists of a split spring-ring r held in a 90 peripheral groove s' on the spindle S and adapted to frictionally engage the interior of the bore b' of the bobbin b. Usually the bobbins or holders b are constructed of wood and the ring r will bite into their bores to 95 hold them against longitudinal displacement.

As before stated, the present improvement is designed particularly for use on creels where a large number of bobbins are arranged to deliver their ends to certain other textile apparatus such, for instance, as a warping machine. It is to be understood, however, that my invention is applicable to other processes where the yarn is to be unwound from the bobbin, it being adaptable 100 for use on winding, gassing, knitting or other like machines. When employed for 105

warp-creels a convenient arrangement is as follows: Referring to Fig. 2, the creel is usually made up of a suitable number of uprights E, only one of which is here shown. 5 These are preferably constructed from channel iron which is trough-like in cross-section, as shown more particularly in Fig. 1. The cross-arms or brackets A are provided with rounded lugs a^3 adapted to fit within the 10 sides of the channeled uprights E and are arranged in series thereon as shown in Fig. 2. Preferably, the curved face of the lug a^3 is formed at an angle to the side of the arm A so that when the latter is placed in 15 position on the upright E the bracket will tilt slightly to bring the spindles S to an inclined position in relation to the upright as shown in Fig. 2. Further angular adjustment of the spindles is accomplished 20 through the setting of their ball-and-socket joints as later described. Suitable bolts e passing through holes in the uprights E are screwed into the lugs a^3 to secure the brackets or cross-arms A in place on the creel. 25 The arrangement illustrated in Fig. 2 provides for the use of "splicer" bobbins on the creel, so-called because their ends are tied or spliced together to provide a continuous delivery of the yarn from two or 30 more supplies. That is to say, the first wound and last-delivering end from one bobbin is spliced to the leading end of the next bobbin so that when the yarn is exhausted from the first supply the next connected bobbin will commence to unwind without break 35 or hindrance in the delivery of the yarn. In this way sufficient yarn can be supplied in each "end" to wind a complete warp by replacing the bobbins as they become exhausted 40 ed without stopping the winding operation to "piece up". It has been found that this method is more practical and economical in use than to provide larger supply-bobbins because the smaller supplies are more convenient 45 to handle and the yarn will deliver from them with greater freedom and uniformity and with less liability of the ends becoming strained or broken.

Any suitable arrangement of tension- 50 means may be employed on the creel for applying tension to the yarns as they draw off from the bobbins and in Fig. 2 I have illustrated one form of such a device. This consists essentially of a porcelain member 55 T having a cylindrical barrel formed with a helical groove t on its periphery. At one end of the member T are two projecting ears or flanges t' , t' having their inner faces diverging to form a V-shaped yarn-receiving 60 groove t^2 . The tension-devices T are mounted on suitable arms or brackets supported on uprights similar to the channel irons E, but these are not here shown or described.

In assembling the bobbin-supports on the 65 creel the cross-arms A are secured in place

on the uprights E in pairs, arranged in such relation that the spindles S of each pair point toward an appropriately-positioned tension-device T. The brackets A of each related pair will be set some distance apart 70 while the first bracket of the next pair will be relatively close to the adjacent bracket of the first pair. In this way a very economical use is made of the space on the creel so that a large number of supplies can be 75 encompassed within narrow limits. Each bracket carries two spindles supporting bobbins delivering to two different tension-devices, and the next bracket supports a pair of bobbins delivering in turn to the same 80 two tension-devices. The angular setting of the arms A on the uprights E provides in a general way for this inclined arrangement of the bobbins B and after the supporting brackets are secured in place a more accurate adjustment of the spindles S is made as 85 follows: By loosening the bolt D the spindles S can be swung on the axis of the bolt in either direction and a more limited, lateral adjustment in the plane of the axis of 90 the bolt is also provided for by the play in the bore s' . In this way the spindles S can be brought into position with their axes pointing directly toward the yarn-receiving notch t^2 of their associated tension-devices 95 T so that the yarns from the appropriate bobbins will lead thereto always at the same angle. In other words, there will be no danger of the yarns drawing off from the 100 ends of the bobbins at sharp angles as they lead to their delivering points. After each spindle has been carefully adjusted as above described its bolt D is tightened to clamp the ball s in its sockets and in this way the spindles are securely held against movement 105 to prevent accidental disarrangement during the doffing and replacing of the bobbins.

In use the creel operates as follows to supply the yarn, thread or other material to the warping or similar machine: The operator fills the creel by placing the bobbins B, B' on all of the spindles and the ends of each pair of supplies are spliced together as next described: The leading end y from one of the bobbins B of each pair is drawn through the guiding-notch t^2 of the appropriate tensioning-device T and then wrapped around the barrel, following the groove t , a suitable number of times to give the required degree of resistance to the draft of 115 the yarn in accordance with the tension required. This end y is then led out to the warping, beaming or other machine to which the yarn is to be delivered. The opposite or last-delivering end y' of the yarn on this 120 same bobbin B is next spliced or tied at α to the leading end y^2 of the bobbin B' of the same pair so that the yarn will be continuous between the two. Usually, when the 125 supply-bobbins are being wound a length 130

of the first end of the yarn is wound about the base of the holder *b* with a few turns, as illustrated at x' in Fig. 2, so that it will be available for use in splicing up. After 5 the splicing of the bobbin is completed the free end of the reserve bobbin *B'* is wound about its surface, as shown at x^2 , Fig. 2, so that no loose loops are left to kink or become tangled and impede the delivery of the 10 material. After the bobbins have all been spliced together in pairs in the manner described the machine to which the yarn is delivered is started and the yarn reeled off as required. When a bobbin *B* becomes exhausted 15 the yarn will be taken off from the next spliced bobbin *B'* and in this way the supply can be maintained continuous as long as desired. That is to say, the operator has only to replace the exhausted bobbin with a 20 full one and to splice up its leading end to the last end of the next delivering bobbin so that the creel can thus be kept supplied continuously without interruption. Through this method a much more economical handling 25 of the material is made possible and no short pieces or waste ends are left on the bobbins after the warp beam is completed.

The present improved means for adjusting the supply spindles makes practical this 30 method of creeling and delivering the yarn as above described. Without such a means for accurately adjusting the spindles to set the bobbins to point directly toward their delivery points it would not be possible to 35 provide a free and unrestricted delivery of the yarn from all of the numerous bobbins. Furthermore, my new device provides for adjusting the spindles so that two or more bobbins can be set to deliver to the same tension-device with a continuous delivery without variations in the tension applied to the 40 yarn. I am aware that it has previously been proposed to employ hinged or swinging bobbin-spindles on creels or other supply-holders, but it is my belief that the present 45 disclosure is the first showing of the use of a universal-joint for this purpose. Through the use of this improvement the supply-spindles can be adjusted easily and quickly 50 with little labor and to assure the required

accuracy in setting the bobbins. I am aware, of course, of the previous use of universal-joints and ball-and-socket connections for various purposes in the mechanical arts, but in the present instance their use is applied 55 to a new purpose and constitutes an improvement over what has gone before. I further believe that a new result is accomplished by this novel use of the means described, and that the advantages derived are 60 very important in the art to which the invention relates.

Various modifications might be made in the form and construction of the parts of my new device without departing from the 65 spirit or scope of the invention; therefore, without limiting myself to the exact arrangement shown and described, what I claim is:—

1. A unitary holder for the cop-spindles 70 of textile apparatus comprising a cross-arm adapted for attachment to a creel-member or other like support and formed with sockets at its extremities, cop-spindles having spherical ends adapted to fit the sockets in 75 said arm, socketed caps fitted to the spherical ends of the spindles, and bolts extending through the caps and screwed into the ends of the arm to clamp the parts together to provide for angular adjustment of the 80 spindles.

2. In a supply-holder for creels or the like, the combination with a creel-member formed of channel-iron, of a cross-arm formed with a rounded lug adapted to fit 85 the trough of the channel-iron, a bolt extending through the channel-iron and screwed into the lug on the cross-arm, spindles for receiving the supply-cops or bobbins, and universal-joints for mounting 90 said spindles at the ends of the cross-arms to adapt them to be adjusted angularly in relation thereto.

In testimony whereof I affix my signature in the presence of two witnesses.

ERNEST A. DE WOLF.
